UNITED STATES PATENT OFFICE.

AUGUST SCHMIDTKE, OF KÖNIGSBERG, GERMANY.

LOCK.

No. 875,291.

Specification of Letters Patent.

Patented Dec. 31, 1907.

Application filed May 24, 1907. Serial No. 375,421.

To all whom it may concern:

Be it known that I, AUGUST SCHMIDTKE, a subject of the German Emperor, and resident of Königsberg, Germany, have invented certain new and useful Improvements in Locks, of which the following is a specification.

This invention relates to improvements in door-locks, and more particularly in such locks as are operated by a hollow latch-key. 10 The object of the invention is to operate the lock not only from one side as hitherto, but from either side of the lock.

In the accompanying drawing, Figure 1 is a view on the lock, the cover being omitted 15 to show the inner parts; Fig. 2 is a section through the key-hole; Fig. 3 a view on the lock, showing a safety-contrivance of the same in inoperative position; Fig. 4 a fragmentary view similar to Fig. 3, in operative 20 position; and Fig. 5 a section through the safety-contrivance.

The lock *a* of any ordinary type, contains below the bar *b* a plate *c* which is movably disposed on two guide-pins *d* and held between 25 springs *e* in the middle between the walls of the lock. The plate *c* carries the key-pintle *f* with the movable key-tube *g* which both project to both sides of the lock. The partition *h* carries a safety-contrivance comprising the lever *i* which with 30 the square bolt *k* is centered on the partition *h* and at its free end provided with a hook *l* which is adapted to project into the slot provided in the key-tube *g* for the insertion 35 of the key. The spring *m* is provided to keep the lever *i* in the engaged position. The insertion of the hook *l* into the slot of the key-tube is necessary as the latter could else be turned by the insertion of an instrument 40 so that the key could not be put in. At the same time, however, the lever *i* affords great security against undue manipulation on the lock, as it covers the lower part of the key-hole.

45 The lock is operated as follows:—First, the lever *i* is turned away from the key-hole by means of a separate key placed on the square bolt *k*. Then, the latch-key is introduced from either side into the key-hole and pushed 50 back so as to press the plate *c* towards the opposite wall of the lock whereupon the key can be turned and the lock opened, while the closing is effected by simply reversing

the movement. After the removal of the key, the plate *c* jumps back to its middle position between the walls under the influence of the springs *e*, while the safety-lever *i* must then be again put into its operative position before the key-hole. 55

Having fully described my invention, what I claim and desire to secure by Letters Patent is:—

1. A door-lock comprising in combination with the lock proper (*a*), its bar (*b*) and the latch-key; a plate (*c*) movably arranged 60 below said bar in the middle between the walls of the lock, guide-pins (*d*) designed to guide said plate, springs (*e*) designed to keep said plate in its mentioned normal position, the key-pintle (*f*) integral with said plate, and 65 the movable key-tube (*g*) provided with a slot for the insertion of said latch-key, both the latter-key-pintle and key-tube-forming the key-hole and projecting to both sides of the lock so as to receive said latch-key from 70 either side of the lock and being capable, through the medium of said latch-key, to be pressed back together with said plate towards the opposite wall of said lock, for the purpose set forth. 75

2. A door-lock comprising in combination with the lock proper, its bar and the latch-key; a plate (*c*) movably arranged below said bar in the middle between the walls of the lock, guide-pins designed to guide said plate, 80 springs designed to keep said plate in the mentioned normal position, the key-pintle integral with said plate, and the movable key-tube provided with a slot for the insertion of said latch-key, both the latter-key- 85 pintle and key-tube-forming the key-hole and projecting to both sides of the lock so as to receive said latch-key from either side of the lock, and a safety-contrivance designed to keep said key-tube in proper position and 90 to cover the lower part of the key-hole and adapted to be turned away from the latter for the insertion of said latch-key, substantially as described and shown. 95

In testimony whereof I have hereunto set my hand in the presence of two subscribing witnesses.

AUGUST SCHMIDTKE.
